US00D861541S

(12) **United States Design Patent** (10) Patent No.: **US D861,541 S**
(45) Date of Patent: **** Oct. 1, 2019**

(54) **RECHARGEABLE BICYCLE PHONE MOUNT**

(71) Applicant: **Shenzhen Grandshine Technology Co., Ltd.**, Shenzhen (CN)

(72) Inventor: **Xuedong Yan**, Shenzhen (CN)

(**) Term: **15 Years**

(21) Appl. No.: **29/635,108**

(22) Filed: **Jan. 28, 2018**

(51) LOC (12) Cl. **12-11**

(52) U.S. Cl.

USPC **D12/114**; D14/253

(58) **Field of Classification Search**

USPC D12/114, 400, 407, 415, 177, 178, 223; D14/253, 252, 251, 447, 432

(57) **CLAIM**

The ornamental design for a rechargeable bicycle phone mount, as shown and described.

DESCRIPTION

FIG. 1 is a perspective view of a rechargeable bicycle phone mount showing my design;

FIG. 2 is another perspective view showing my design;

FIG. 3 is a front view showing my design;

FIG. 4 is a back view showing my design;

FIG. 5 is a left side view showing my design;

FIG. 6 is a right side view showing my design;

FIG. 7 is a top plan view showing my design; and,

FIG. 8 is a bottom plan view showing my design.
